COMBINED ARMCHAIR AND BED DEVICE

Hortensia Lamar and Francisco de P. Moreno,
Marianao, CubaApplication October 11, 1929, Serial No. 399,025
In Cuba May 27, 1929

3 Claims. (Cl. 155—30)

This invention relates to improvements in combined chairs and beds, the object of the invention being to provide an article of this kind which is especially adapted for use by invalids and which is ambulant and may be readily moved by the occupant from place to place.

With the above and other objects in view, the invention consists in the construction, combination and arrangement of devices hereinafter described and claimed.

In the accompanying drawings

Figure 1 is a side elevation of my improved combined chair and bed showing the same arranged for use as a bed.

Figure 2 is a plan of the same.

Figure 3 is a front elevation of the same arranged for use as a chair.

Figure 4 is a detail elevation of the supporting frame for the rear end of the bed and back member.

Figure 5 is a detail elevation partly in section of the main frame, the seat frame and the connections between the seat frame and the foot rest.

Figure 6 is a detail plan of the same.

Figure 7 is a detail elevation partly in section of the main frame, the seat frame, the back frame, the adjusting-means for the seat frame and the connections between the seat frame and the foot rest.

The main frame 1 is substantially U-shaped and is open at the front side and is provided at the front ends of its side arms with brackets 2 which are secured thereto by rivets or the like and depend therefrom. Said brackets are each provided with a vertical slot 2^a and through the said slots extends the cross sectionally rectangular portion of the axle 3 which is held in the bottom of the slot by any suitable means such as a block 3' which is secured by a bolt 3''. Wheels 4 are mounted on the axle and are each provided on the outer side with a hoop 4' as usual, to enable the wheels to be manually turned by the occupant of the chair so that the occupant of the chair can wheel himself about. At the center of the rear cross bar of the frame 1, which as shown in Figure 3 is cranked or downwardly bowed, is a bearing member 5 which is secured thereto and in which is swivelly mounted the upper end of the standard of a fork 6 in which a rear wheel 7 is mounted. Wheels 4 and 7 in practice have a cushioning tire.

A substantially U-shaped frame 9 which when in horizontal position forms a bed frame and which when in raised inclined position forms a back frame for the chair, is preferably in prac-

tice made of angle iron and the forward ends of its side arms are pivoted as at 8 to the outer sides of the arms of the main frame 1 at points near the rear end of said frame. Supporting legs 10 have their upper ends pivotally connected to the sides of the frame 9 near the rear end of the latter and are provided at their lower ends with casters or rollers 12. Said legs are connected by a bar 11 which is braced as shown, and said legs are also connected to the sides of the frame 9 by pairs of links 13, 14, the said links being pivoted at their outer ends as at 15 and pivotally connected together as at 15'. Braces 16 are pivotally connected to the links 14 and their upper ends are detachably connected to the pivots 16^a by which the legs 10 are connected to frame 9. Hence when the frame 9 is raised to the position shown in dotted lines in Figure 1, and in full lines in Figure 3, the legs 10 may be folded downwardly out of the way by first disengaging the braces 16 from the pivot 16^a, as will be understood.

A U-shaped seat frame 18 which is open at its rear side and which in practice is preferably made of angle iron, is arranged between the side arms of the main frame 1, and the rear ends of its side arms are pivotally connected to the opposite sides of said frame 1, as by means of pivots 17. Hence the front end of said seat frame may be raised and lowered. When lowered to horizontal position and arranged substantially level with the frame 1, the said seat frame forms a part of a bed as shown in Figures 1 and 2. When the article is used as a chair, said seat member may be arranged either horizontally or at any desired inclination. To support said seat frame at any desired adjustment, the same is provided at its front end with depending standards 27 which are pivotally connected at their upper ends to said seat frame as at 28 and which are each provided with a series of downwardly extending open slots 29. By appropriately engaging the axle 3 in certain of the slots 29, the seat frame may be secured in adjusted position.

A substantially U-shaped foot frame 23 which is open at its rear side and which is preferably made of angle iron is arranged in front of the seat frame and is connected thereto by links 21, the front ends of said links being pivotally connected to the rear ends of the arms of said foot frame by pivots 22, and their rear ends being secured as at 20 to corner brackets 19, which brackets are secured as by means of rivets or the like to the front side of the seat frame. Hence the foot frame may be arranged either in horizontal position as shown in Figures 1 and 2 to form in con-

nection with the frames 18 and 9 a bed frame, or said foot frame may be swung downwardly to any desired inclined position. Said foot frame is held in any desired adjusted position by braces 5 26, each of which is pivotally connected at its rear end as at 26^b to the lower end of one of the standards 27 and is adjustably and detachably pivotally connected at its front end to one side of the foot frame 23. Each said brace has a 10 pivot stud 26^a at its front end which may be engaged in any of the series of adjusting openings 23^a with which the sides of the foot frame are provided. At the front end of the foot frame is a 15 foot rest 25 which has irons 24 at its ends, the lower ends of which are pivotally and adjustably connected to the sides of the foot frame 23 at points near the front end of said foot frame. A 20 suitable fabric 30 for the bed, the foot frame, and the chair seat and back is arranged longitudinally in the frames 9, 18 and 23, and is here shown as held by spring links 31.

The frame 9 when in raised position is held 25 adjustably by links 32, the lower ends of which are pivotally connected to the sides of the frame 1 by pivots 33 and the upper ends of which are provided with pivot studs 34 which may be inserted in any of series of adjusting openings 34^a with which the sides of said frame 9 are provided.

The arms 35 may be of the form here shown 30 or any other suitable form and are hingedly connected as at 36 to the upper ends of standards 37, the lower ends of which are secured to the sides of the frame 1. Cross braces 38, 39 are provided for said standards and are secured thereto and 35 also to the sides of frame 1 as shown. Said arms may be arranged either in horizontal or in vertical position, as will be understood, and as shown in Figures 1, 2 and 3.

Having thus described our invention, we claim:

1. A combined chair and bed, comprising a 40 main frame, an axle and wheels carrying the main frame, a frame composed of a seat member, a member adapted to have a horizontal position and when in horizontal position to form a portion of a bed and when in inclined position to form a back, and a foot member, the said seat and bed and back forming members being pivotally connected on adjacent points to the main frame and the foot member being pivotally connected to the seat member, legs pivotally con- 45 nected to the seat member, standard links secured to the sides of the seat member and provided with a series of open notches each adapted to engage the axle to adjustably hold the seat member in an inclined position when so desired, braces, and means adjustably connecting the braces to the sides of the foot member and to the free end of said standard links.

nected to the bed and back forming member, standard links secured to the sides of the seat member and provided with a series of open notches each adapted to engage the axle to adjustably hold the seat member in an inclined position when so desired, braces, and means adjustably connecting the braces to the sides of the foot member and to the free end of said standard links.

2. A combined chair and bed comprising a main 10 U-shaped frame, a pair of brackets secured to the sides of said main frame, a horizontal axle carried on said brackets, wheels on said axle, a vertical fork rotatably mounted at the center of the cross portion of said main frame, a third wheel rotatably mounted on said fork, a frame 15 composed of a seat member, a member adapted to have a horizontal position and when in horizontal position to form a portion of a bed and when in an inclined position to form a back, and 20 a foot member, each of said members being U-shaped end of angular transverse cross section, 25 said seat and said bed and back forming members being pivotally connected in opposite relation to each other on adjacent points of the main frame and said foot member being pivotally connected by links to the seat member, standard links secured to and hanging from the sides of the seat member and each provided at one lateral edge with a series of open notches adapted to engage the 30 axle in order to adjust the inclination of the seat member with respect to the main frame, braces connecting the sides of the foot member to said standard links, legs pivotally connected to the bed and back forming members, uprights connected by screw bolts to the sides of the main frame, supporting pieces secured to said uprights and horizontal boards hinged to said supporting pieces.

3. In a wheel chair, a main frame, an axle 40 connected to said main frame, a seat frame pivotally connected to the main frame for angular movement in a vertical plane, standard links depending from the seat frame and adjustably connected to the axle, a foot frame pivotally connected to the front end of the seat frame and 45 braces connecting the sides of the foot frame and the free ends of the standard links.

HORTENSIA LAMAR.
FRANCISCO DE P. MORENO.
